(57) **CLAIM**

I claim the ornamental design for an outsole, as shown and described.

DESCRIPTION

FIG. 1 is a bottom plan view of an outsole showing my new design;

FIG. 2 is a right view of the outsole in accordance with the embodiment of the new design shown in FIG. 1;

FIG. 3 is a left view of the outsole in accordance with the embodiment of the new design shown in FIG. 1;

FIG. 4 is a front view of the outsole in accordance with the embodiment of the new design shown in FIG. 1;

FIG. 5 is a back view of the outsole in accordance with the embodiment of the new design shown in FIG. 1; and,

FIG. 6 is an enlarged cross-sectional view taken on line 6—6 of FIG. 1; the broken lines showing the interior surface being understood to form no part of the claim.

1 Claim, 5 Drawing Sheets
